[57] CLAIM

The ornamental design for a simulative doll house, as shown and described.

DESCRIPTION

FIG. 1 is a front elevational view of a simulative toy doll house showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a front elevational view with the front closed. Portions of the front cover member have been shown in fragment in FIGS. 3 and 4 for ease of illustration.
